HEAT RETAINING DRUM FOR FURNACES AND THE LIKE

Ernest Hirter, Dundee, Oreg.

Application April 23, 1940, Serial No. 331,221

2 Claims.

(Cl. 126—106)

The present invention relates to heating plants, such as furnaces, circulating heaters, stoves and the like, and has for its primary object to provide a heat retaining drum mounted in the combustion chamber of the furnace and adapted to collect and retain a portion of the heated gases within the furnace to more effectively utilize such heated gases before permitting the same to escape through the smoke stack.

An important object of the present invention is to provide a heat retaining drum of this character which is adjustable to furnaces or stoves of various sizes in order to reduce the number of sizes of the heat retaining drums to be carried in stock for installing in furnaces having combustion chambers of various sizes.

A further object is to provide an attachment of this character of simple and practical construction, which is efficient in performance, relatively inexpensive to manufacture and install in operative position and otherwise well adapted for the purposes for which the same is intended.

Other objects and advantages reside in the details of construction as more fully hereinafter described and claimed, reference being had to the accompanying drawings forming part hereof wherein like numerals refer to like parts throughout, and in which—

Figure 1 is a vertical sectional view through a conventional type of hot-air furnace showing the heat retaining drum mounted in position therein,

Figure 2 is a transverse sectional view taken substantially on a line 2—2 of Figure 1,

Figure 3 is a fragmentary vertical sectional view showing the cold air intake pipe,

Figure 4 is a group perspective view of the heat retaining drum,

Figure 5 is a similar view of the adjustable extension at the lower end of the drum,

Figure 6 is a similar view of the pipe provided for connecting the hot-air chamber of the furnace with the hot-air chamber of the heating drum, and

Figure 7 is a top plan view of the heat retaining drum.

Referring now to the drawings in detail, the numeral 5 designates a hot-air furnace of conventional construction and which includes the outer shell 6 and the inner shell 7 to define the hot-air chamber 8 therebetween. The fire-box is shown at 9 for heating the interior of the inner shell 7 and connected thereto, adjacent its upper portion, is the smoke stack 10.

The top of the inner shell 7 is provided with an opening 11 within the edges of which is snugly

fitted the heat retaining drum designated generally at 12. The heat retaining drum includes a tubular member 13 having an outturned flange 14 at its upper end which is bolted or otherwise secured to the top of the inner shell 7, as shown at 15.

Arranged vertically in the tubular member 13 is the tubular heat trap 16 having its walls spaced from the member 13, the trap 16 being open at its bottom and closed at its top and supported at its upper end in spaced concentric relation in the tubular member 13, by spacing bars 17. The bottom portion of the trap 16 is flared as shown at 18 with its lower extremity 19 having its walls snugly fitted within the lower portion of the tubular member 13. An air chamber 20 is thus formed between the tubular member 13 and the trap 16 which is closed at its bottom and communicates at its upper end with the hot air chamber 8. The lower portion of the hot air chamber 20 has atmospheric communication by means of a plurality of horizontal pipes 29 extending through the inner shell 7 and the outer shell 6 and having their end portions welded or otherwise permanently secured to the tubular member 13 and said outer shell. Cold air may be admitted into the chamber 20 by means of a vertically disposed pipe 30 having a horizontal upper end 31 inserted into the pipe 29, the lower end of the pipe 30 being open.

Telescoping upwardly over the lower end of the tubular member 13 is a tubular extension 21 adapted for retaining in vertically adjusted position by means of a bolt 22 inserted in the vertically extending slotted opening 23 of the extension and through the opening 24 of the tubular member 13. Slotted openings 21' accommodate the pipes 29. The lower end of the extension 21 tapers inwardly as shown at 25 to provide a reduced opening 26 in its bottom portion. The walls of the tubular member 13 adjacent its lower end as well as the walls of the extension 21 are provided with registering openings 27.

From the foregoing it will be apparent that the heat retaining drum serves to retain a portion of the heat from the combustion chamber of the furnace and thus more effectively utilize the gases for heating the air in the hot air chamber 8 and the hot air chamber 20 before permitting the heated gases to pass through the smoke stack 10.

When desired the plate 28 on top of the furnace may be removed and a hot air register substituted therefor, or a suitable duct connected to

the furnace for conveying the heated air to a desired location.

The extension 21 may be adjusted to suit the particular size of furnace in which the heat retainer is mounted and it will be obvious that the air in the chamber 20 will be heated to a higher degree than the air in the chamber 8 whereby a circulation of the air will be produced.

The inwardly inclined lower edge 25 of the heating drum forms a deflector for directing the heated gases toward the side walls of the furnace. The openings 27 in the side walls of the heating drum adjacent the lower end thereof, are provided to produce a better circulation of the heated gases into and out of the drum. It will be apparent that should a high flame rise from the fire bed 9 and enter the lower opening 26 of the drum, that it is necessary to permit the escape of the heated gases from the drum in order not to create back pressure which would tend to smother the flames. Accordingly, the openings 27 accomplish this purpose.

It is pointed out that the openings 27 will not at any time be entirely closed since upon the lowering of the extension 21, the opening 27 in the extension will be moved below the lower edge of the tubular member 13.

The adjustment of the extension 21 enables the opening 26 at the lower end thereof to be moved toward or away from the fire bed to permit an adjustment thereof in accordance with the size of the furnace and the size of the flame contained therein.

It is believed the details of construction, operation and advantages of the device will be understood from the foregoing without further detailed explanation.

Having thus described the invention, what I claim is:

1. An attachment for furnaces and the like comprising a container composed of a pair of telescoping sections, means for suspending the container in the combustion chamber of the furnace, the lowermost of said sections having apertures constituting intake and discharge ports for admitting heated gases into the uppermost section and discharging the same therefrom at a point above the lower edge of the container, said lower section having an inwardly inclined lower edge constituting a deflector for directing heated gases toward the side walls of the furnace, and means for securing the lowermost section in vertically adjusted position relative to the uppermost section.
2. An air heating furnace comprising in combination, an inner shell constituting the combustion chamber and an outer shell spaced therefrom and constituting an air chamber, a tubular member suspended from the top of the inner shell, a tubular trap having a closed top supported concentrically in the member to provide a second air chamber between the walls of the trap and the walls of the member, said last named air chamber being closed at its bottom and open at its top for communication with the interior of the first mentioned air chamber, conduits providing atmospheric communication for said last named air chamber, and a tubular extension adjustably connected on the lower end of said first named member having openings in its walls, said extension having a restricted mouth movable toward and away from the heating agent of the furnace.

ERNEST HIRTER.
